UNITED STATES PATENT OFFICE

JACOB H. LINVILLE, OF PHILADELPHIA, PENNSYLVANIA.

PRINTING-TELEGRAPH.

SPECIFICATION forming part of Letters Patent No. 368,217, dated August 16, 1887.

Application filed October 4, 1886. Serial No. 215,224. (No model.)

To all whom it may concern:

Be it known that I, JACOB H. LINVILLE, of the city and county of Philadelphia, in the State of Pennsylvania, have invented certain new and useful Improvements in Printing-Telegraphs; and I do hereby declare the following to be a full, clear, and exact description thereof, reference being had to the accompanying drawings, forming part hereof.

10 My invention relates, especially, to that class of printing-telegraphs operating automatically, either as transmitters or receivers, by electrical pulsations sent from any instrument organized as a transmitter over a conductor connected with one or more similar instruments 15 organized as receivers when the type-wheel shaft is driven by any suitable motive power. It relates, further, to the application of a 20 motor to automatically wind a spring which rotates the type-wheel shaft; in the use of two type-wheels in page-printing telegraphy whereby, through suitable shifting devices, the 25 impressions upon the paper from either wheel may be made in the same continuous line; in improved apparatus for presenting the paper in page form from a continuous roll to the type-wheels, and in electro-magnetic devices and circuits to operate the type-wheels to unison the type-wheels and paper-carriages and 30 to effect impressions.

The general object of my invention is to diminish the cost, to increase the rapidity and certainty of such apparatus, to obviate the necessity of winding the motive power by hand, 35 and to provide improved means of maintaining synchronism between the pulsator and the type-wheels of the instrument employed as a transmitter and the type-wheels of the instruments employed as receivers, whereby their 40 synchronous movement is automatically adjusted, when necessary, once in each revolution by an electro-magnet responding to pulsations of twice the ordinary length required to rotate the type-wheels, without retarding 45 the regular motion of the type-wheels of the transmitter, and to effect the requisite operations over a main conductor by the aid of local batteries, using in all the operations currents of similar polarity.

50 My invention consists—

First, in the employment of an electromotor to automatically wind a spring interposed

between a drum carrying a toothed gear-wheel engaging with a pinion on the type-wheel shaft and a shaft passing through the drum, 55 around which a spring is continuously or intermittently wound by means of a gear-wheel secured to said shaft through intermediary gearing driven by a pinion on the motor-shaft.

Second, in the peculiar construction of a 60 table of insulated segments equal in number to the divisions of the type-wheels placed concentric with the type-wheel shaft, over which segments traverses a brush secured to a metallic hub on the type-wheel shaft and insulated 65 therefrom. An insulated contact-spring in electrical connection with the main-line circuit bears on this metallic hub. In the table of contacts, usually termed a "sunflower," the segments are alternately connected by conductors to open and closed circuit-springs operated by the stems of the keys on the key-board, except in one instance, where three consecutive contacts are connected with closed 70 circuit-springs of the key-board. The anvils 75 of the circuit-springs are electrically connected with one another and with one electrode of the line-battery.

Third, in the use of a double-point relay with its coils in the main-line conductor, both 80 in the transmitting and receiving instruments, the tongue of the double-point relay being connected with one electrode of a local battery, while its front and back contacts are respectively connected by conductors to the parallel 85 coils of the escapement electro-magnets and to the other electrode of the local battery.

Fourth, in the use of neutral escapement electro-magnets wound with parallel coils, between the poles of which electro-magnets polarized armatures are caused to vibrate in response to currents of similar polarity traversing the parallel coils in reverse directions.

Fifth, in the employment of two type-wheels, one engraved with the letters of the 95 alphabet, blanks, punctuation-marks, &c., and the other with numerals, fractions, conventional signs, blanks, &c., both being rigidly secured to a sleeve moving loosely on the type-wheel shaft, with means for shifting the type-wheels vertically, and means for effecting the printing of letters, characters, and numerals 100 in the same continuous lines and in page form on sheets of paper or from rolls of paper.

Sixth, in a circuit "director," by which, when the type-wheels are arrested at determinate points, the currents from a local battery are automatically directed through the 5 coils of the respective electro-magnets employed to shift the type-wheels, feed the paper, release the paper-carriage, or effect impressions.

Seventh, in an improved unison device controlled by a circuit "corrector," whereby a continuous local current, due to the prolonged contact of the relay-tongue on the front stop during the passage of the brush over three successive closed circuit-contacts in the sunflower, is subdivided into three distinct impulses—one to energize the escapement electro-magnets and advance the type-wheels when the main line is closed, one which passes through the other coil of the escapement electro-magnets, reversing their polarity when the main line is ordinarily broken, and another which again reverses the polarity of the escapement electro-magnets when the main line is normally closed, whereby a regular succession of electrical impulses in the local circuits through the escapement electro-magnets is effected, permitting uninterrupted rotation of the type-wheels during a prolonged impulse over the main line, while at the same time the coils of the unison electro-magnet are included in the local circuit by the corrector during the time of two consecutive local-circuit pulsations through the escapement electro-magnets. The unison electro-magnet is preferably adjusted so as to respond only to such prolonged pulsations.

The motor, being constantly in the closed circuits of a local battery, winds the coiled spring until arrested by a Geneva stop, or by 40 an electrical cut-out controlled by said Geneva stop, the coiled spring constantly tending to revolve the drum and gearing which turn the type-wheel shaft. The revolution of this shaft is controlled by an anchor-escapement, the 45 pawl-lever of which carries a polarized steel armature, vibrating between unlike poles of two opposing neutral electro-magnets wound with two parallel coils. When the circuit of the main-line battery is closed through a sunflower-contact, the armature of the relay is attracted, and the circuit of a local battery is closed by the relay-tongue through the front contact in one direction, through one of the coils of the escapement electro-magnets, which imparts 50 motion to a polarized armature, permitting a movement of the type-wheel shaft corresponding to one division of the type-wheels, and the contact-brush is thereby moved to an open-circuit segment of the sunflower, whereupon 55 the main-line circuit is broken and the relay-tongue falls against its back stop, closing the local circuit in a reverse direction through the second coil of the escapement electro-magnets, and thereby reversing their polarity and 60 moving the polarized armature in a reverse direction, permitting the type-wheel shaft to revolve another step, whereby the contact- 65

brush is placed on a closed-circuit segment and the previous operation is repeated, the type-wheels continuing to rotate by the constant force of a coiled spring or other suitable power until a key is depressed, which causes two consecutive makes or breaks of circuit on the sunflower, thereby interrupting the alternate succession of makes and breaks of circuit and arresting the vibrations of the relay-tongue in contact with either its front or back stop. The type-wheels are consequently stopped at a character corresponding with the key connected to that segment of the sunflower on which the brush is arrested. When the key is released, the alternation of closed and open circuit contacts is restored and the type-wheel shaft continues to revolve until again arrested. The pulsations over the line 85 operate the relays in one or more receivers, the line passing around the sunflower and the key-board directly from one receiver to another in series and then to ground. The change from a transmitter to a receiver is effected by reversing an ordinary two-point switch.

The shifting of the type-wheels vertically is effected by a local battery the circuit of which is closed by the director at certain positions of the type-wheels through electro-magnets operating the shifting devices. Similarly, at other positions of the type-wheels, the local circuit is closed by the director through the impression and paper-feeding electro-magnets. 90 The unison electro-magnet has a projection on its armature-lever normally in the path of a unison-arm attached to the type-wheel shaft, and which projection will arrest the type-wheels in the unison position unless withdrawn by a prolonged pulsation, occurring when the unison-arm arrives in contact therewith. This pulsation can pass through the coils of the unison electro-magnet only when a prolonged line-current energizes the relay 105 electro-magnet and when the corrector and type-wheels of the receiver are within one step of the unison position; hence if the type-wheels of a receiver are not moving synchronously with the type-wheels of a transmitter they will be arrested on arriving at the unison position until a prolonged pulsation occurs in the main line at and just preceding the unison position of the transmitter, simultaneously releasing the unison-arms of both instruments by a pulsation in the local circuit through the coils of the unison electro-magnet of twice the duration of the normal pulsations which energize the escapement electro-magnets without checking the motion of the type-wheels, as is the case where the unison and escapement electro-magnets both respond to the same prolonged impulses in the same line. 115

The paper is preferably fed from a continuous roll and spaced between the lines of printing thereon by the action of an electro-magnet operating devices different from those shown in my previous Letters Patent, and the paper-carriages are brought into unison by continu-

ing the pulsations until they are all arrested at the end of their forward movement, when all the carriages are simultaneously released by magnetic devices, which not only release 5 the pawl and dog of the spacing-rack, but also release a counter-pawl engaging in a counter-rack introduced to promptly check the movement of the paper-carriage when advanced suddenly to space rapidly between letters.

10 An improved signaling device to indicate to the transmitting-operator when the paper-carriage of the receiver has completed its recoil movement operates as follows: The main-line circuit is looped through spring-contacts 15 normally closed at the transmitters and receivers, and the key that is employed to close the main-line circuit and arrest the type-wheels at a blank space in position for the directors to close the local circuit through the electro-magnets which operate to release the paper-carriages short-circuits this loop at the transmitter. The paper-carriage of the receiver when recoiling separates these contacts, thereby momentarily interrupting the main-line circuit, and the relay-tongue consequently strikes 20 its back stop, changing the local circuit through the escapement electro-magnets, and the type-wheels of both instruments consequently make one revolution, being again arrested when the brush reaches the segment of 25 the sunflower connected with the depressed key. This abnormal movement of the type-wheel will, with certainty, indicate the recoil of the paper-carriage of the receiver, and the 30 operator will thus be enabled to correct any irregularity in the movement of the respective paper-carriages before printing a succeeding line.

My invention also comprises numerous details of mechanism hereinafter fully explained.

In the accompanying drawings, illustrating my invention, Figure 1 is a plan view of the key-board and paper-carriage and a plan of the interior of the apparatus below a horizontal plane cutting the instrument above the scape-wheel and the escapement electro-magnets. Fig. 2 is a longitudinal section through the body of the key-board and instrument and a side elevation of the bracket and impression electro-magnet and mechanical devices. Fig. 3 is a transverse section of the apparatus taken in rear of the type-wheel shaft. Fig. 4 is a horizontal section through the base of the instrument and through the bracket supporting the impression devices, and showing also a detail of the winding-drum and Geneva-stop cut-out. Fig. 5 is a rear elevation of the instrument. Fig. 6 is a top view of the box of the instrument and of the paper-carriage and impression devices. Fig. 7 is a detail of the respective disks and circuit-springs composing the director. Fig. 7^a is a vertical longitudinal section of the director. Fig. 8 is a detail of the respective disks and circuit-springs 55 composing the corrector. Fig. 9 is a diagram indicating the direction of the current in an

ordinary electro-magnet, with two cores united by a pole-piece. Fig. 10 is a diagram of the core and coil of an electro-magnet as ordinarily wound, showing the polarity when the positive current circulates in the direction indicated. Fig. 11 is a diagram of two electro-magnets with opposing poles, the coils of which are all wound similarly to the winding illustrated in Fig. 10, but with two parallel coils. The coils show the direction of the currents of similar polarity, and the resulting reverse polarity of the opposite poles is indicated. Fig. 12 is a diagrammatic view of the complete circuits of the line and local batteries through the circuit-controlling devices and electro-magnets of an instrument organized as a transmitter, and Fig. 13 is a diagrammatic view of the complete circuits of the line and local batteries through the circuit-controlling devices and electro-magnets of an instrument organized as a receiver.

Referring to the drawings, O represents a suitable case inclosing portions of the instrument. A key-board, O², rests on and is detachable from the case O. The bed-plate O⁵ is secured to the case by lugs O¹², and on this bed-plate is constructed the removable upper case, consisting of the corner-pieces O⁶, posts O⁷ O¹¹, front plate, O¹³, top plate, O¹⁰, and bevelled glass side plates, O⁸. By removing the long screws O¹⁴ the corner-pieces O⁶, may be taken out, and the glass sides may then be removed, affording access to the interior of the apparatus without removing the top plate, O¹⁰.

On the base O' is secured the plate O¹, of insulating material, to which are secured the insulating strips O¹⁷, and to which the circuit-springs O¹² and O¹⁶, the anvil-bars O¹³, and the stops O¹⁵ are fastened. The anvil-bars O¹⁴ are insulated from the key-board O². Through the removable key-board O² and the guides O⁹ pass the stems O⁸ of the open-circuit keys O and the closed-circuit keys O'. The stems of these keys are provided with helical springs O¹⁰ and with terminals O¹¹, of insulating material, in contact with the circuit-springs O¹² and O¹⁶, and also with stop-pins O¹⁸, to limit their upward movement.

The anvil-bars O¹³ limit the downward movement of the circuit-springs O¹², and the stops O¹⁵ determine the movement of the circuit-springs O¹⁶. The keys O and O' are engraved with letters of the alphabet, characters, numerals, fractions, punctuation-marks, &c.

The key O², marked "Up," is used to arrest the type-wheels at a predetermined point, in order to actuate the several devices to raise them. To lower the type-wheels, the key O³, marked "Down," is employed. The key O⁶ is depressed when spacing between words or advancing the paper-carriage, the key O⁴ to feed the paper between lines, and the key O⁵ is depressed when it is desired to release the paper-carriage at any point in its excursion. The plate U is sustained by posts u, secured within the bed-plate O', and forms the support

for the type-wheel shaft R and the shaft v^{12} . The flanged ring u^3 is supported by the plate u^2 , which supports the sunflower S.

The sunflower S consists of thirty-two metallic segments, as shown in Figs. 12 and 13, equally spaced around and concentric with the type-wheel shaft R. These segments are insulated from each other and from the bed-plate O⁶. The segments marked s^7 are connected by the conductors 7 to the circuit-springs o^{16} , and the segments s^8 by the conductor 6 to the circuit-springs o^{12} . Three successive contacts, s^7 , of the sunflower S are connected with closed circuit-springs o^{16} , while all the remaining segments are alternately connected to circuit-springs o^{16} and o^{12} . The metallic hub s is secured to and insulated from the type-wheel shaft R, and carries an arm, s^2 , to which is adjusted the brush s^3 , bearing on and arranged to traverse the segments s^7 and s^8 when the type-wheel shaft revolves. The contact-spring s^4 , insulated at s^5 from the instrument, bears on the metallic hub s and is in connection with the conductor 8 of the line-circuit. During the revolution of the type-wheel shaft and brush alternate makes and breaks of circuit of uniform duration will occur in the main-line circuit until the brush passes three successive closed contacts, which will then produce a prolonged impulse in the line-circuit without checking the regular progressive movement of the type-wheel shaft effected through the intervention of the corrector, as hereinafter more particularly described.

Rotary motion of the type-wheel shaft R is effected by the spur-wheel v, secured to the drum V, engaging in the pinion-wheel v^7 on the shaft R, the drum V being constantly revolved by a coiled spring, v^8 , secured to the interior of the drum and to the shaft v^{12} . This shaft v^{12} is constantly turned by a suitable motor, C, through the intervention of miter-wheels v^9 and v^{10} and a pinion, v^{11} , engaging in the spur-wheel v^2 , secured to the shaft v^{12} , thus continuously winding the coiled spring v^8 until arrested by a Geneva-stop pinion on the shaft v^{12} locking in its gear-wheel v^{10} on the spur-wheel v, or, preferably, until the motor-circuit is temporarily interrupted at a predetermined point in the revolution of the Geneva stop. The cam v^{16} on the gear-wheel v^{10} passes under the insulated pin v^{19} , sliding in the metal wheel v^{20} , insulated from the shaft v^{12} , and by raising the pin v^{19} , which impinges against the circuit-spring v^{21} , lifts this spring clear of the metal wheel v^{20} , thereby interrupting the motor-circuit, which is again closed when the drum V and spur-wheel v² are advanced by the force of the coiled spring, and by which arrangement a uniform tension of the coiled spring v^8 is maintained. The motor-circuit may be shunted in any well-known manner through a resistance equivalent to the combined resistance of the motor-armature and field-magnets. When the motor-circuit is temporarily interrupted, the shaft v^{12} is prevented

from recoiling by a click, v^{13} , engaging in the ratchet v^{14} on the shaft v^{12} .

The step-by-step motion of the type-wheel shaft is controlled by a polarized armature, p, carrying pallets p^3 and p^4 , engaging in the scape-wheel p^5 on the type-wheel shaft R. This armature is caused to vibrate by alternate reversals of the polarity in the adjacent poles of the double-coil neutral-escapement electro-magnets P, P', P², and P³, due to the change of direction of the currents of similar polarity traversing these coils. Alternate makes and breaks of the main-line circuit through the brush s^3 respectively magnetize and demagnetize the relay D, causing its tongue d to vibrate between its front stop, d^1 , and back stop, d^2 , alternately closing the circuit from one pole of the local battery B' through the corrector L and the electro-magnets P, P', P², and P³, causing corresponding vibrations of the polarized armature p, and consequently a step-by-step movement of the scape-wheel p^5 , type-wheel shaft R, and brush s^3 , as will be hereinafter more fully explained. Consequently when the switch W is turned to the point w, Fig. 12, and the point w', Fig. 13, and the circuit of the main-line battery B is thereby closed through the key-board and sunflower and the relay of the transmitter, and through the relay to ground at the receiver, the relays of the transmitter and receiver will be simultaneously energized, and the type-wheels of both instruments will continue to revolve synchronously until the alternate succession of closed and open circuit contacts is interrupted by depressing a key, o or o', which causes the brush s^3 to contact with two consecutive closed or open circuit segments in the sunflower, arresting the vibrations of the relay-tongues d, and stopping the vibration of the polarized armatures p and pallets p^3 and p^4 , and stopping the scape-wheels p^5 and type-wheels R' and R² at a character corresponding to the key depressed on both transmitters and receivers. When the key is released, the alternate succession of impulses in the main line is thereby restored, and the shaft R continues to revolve until again arrested by depressing a key or by breaking the line-circuit at the switch W, as hereinafter more particularly described.

The director M (shown in detail in Fig. 7 and in the dissected views in Fig. 7) is secured to the shaft R by means of hubs m and m^2 , set-screws m^{36} and m^{37} , the pins m^{34} and m^{35} , combining the insulating-collars m^{30} and m^{31} with the hubs, and the insulating-sleeves m^{32} and m^{33} . The metallic sleeves m^1 and m^3 are prolonged until they reach the separating-disks of insulating material m^{25} and m^{26} . The metallic disks m^2 , m^3 , and m^4 are in electrical contact with the sleeve m^1 , and the metallic disks m^5 , m^6 , and m^7 are in a like manner in contact with the sleeve m^3 , and the metallic disks are separated from one another by insulating-rings m^{22} , m^{23} , m^{24} , m^{25} , m^{26} , m^{27} , m^{28} , and

m^{29} . The spring m^{13} bears on the sleeve m' , and springs m^{11} , m^{12} , and m^{13} bear, respectively, on the metallic disks m^2 , m^3 , and m^4 . Similarly, the spring m^{17} bears on the sleeve m^8 , and the springs m^{14} , m^{15} , and m^{16} bear, respectively, on the metallic disks m^5 , m^6 , and m^7 . I have shown a corrector with thirty-two divisions, corresponding with the number of divisions on the sunflower and the number of characters on the type-wheels. These numbers must correspond in all cases; but a greater or less number in each would operate equally as well. There are thirteen exterior metallic contacts, m^{38} , on the disk m^2 and fourteen contacts, m^{35} , on the disk m^7 at regular intervals on the periphery, except where one regular contact is omitted, as at m^{39} , m^{40} , m^{16} , and m^{47} . The contact corresponding to the division m^{39} is on disk m^3 at m^{41} , and the contact corresponding to m^{40} is on disk m^4 at m^{42} . The contact corresponding to the division m^{36} on disk m^7 is at m^{43} on the disk m^5 , and the contact corresponding to the division m^{47} on the disk m^7 is on the disk m^6 at m^{44} . The contacts m^{38} on the disk m' alternate with the contacts m^{45} on disk m^7 , and it follows that if the director M is stopped at any one of its thirty-two subdivisions electrical contact will be made through the particular spring resting on the contact corresponding with that subdivision, and the metal sleeve m' or m^8 and the spring m^{10} or m^{17} and all other peripheral contact-springs will rest on insulated spaces separating the metallic disks.

35 The peripheral contact-springs m^{11} and m^{16} are in the local circuit of battery B' through the coils of the electro-magnets F, employed for moving the paper-carriage to space between letters, and through the coils of the electro-magnet G, for making impressions. The spring m^{12} is in circuit with the coils of electro-magnet H for lifting the type-wheels, and the spring m^{15} in the circuit of the electro-magnet H' for lowering the type-wheels. The spring m^{13} is in the circuit of the electro-magnet I for feeding the paper to space between lines, and the spring m^{14} is in the circuit of the electro-magnet J to release the dog f^{15} and the pawl f^2 and counter-pawl f^9 from the spacing-rack f^5 and counter-rack f^7 of the paper-carriage at any point in its excursion. The peripheral contacts are shorter than the intervening insulations, so that the momentary closing of the local circuits during the rapid revolution of the director is not of sufficient duration to energize the electro-magnets in circuit, so as to overcome their retracting-springs; but when the shaft R and the director M are arrested by the depression of any key the corresponding peripheral contact of the director rests under its respective circuit-spring, and a prolonged impulse results, strongly energizing the particular electro-magnet through the coils of which the circuit is thus directed.

65 The construction of the corrector L, which is secured to but insulated from the shaft R, is similar to one division of the director M, as

illustrated in Fig. 7^a. The metal disks l^2 , l^3 , and l^4 are in electrical contact with the insulated metallic sleeve l' , and are separated by 70 insulating-disks.

The spring l^8 in the circuit of the local battery B', through conductor 11, tongue d, and the front stop, d^4 , of the relay D, rests on the metal sleeve l' , and the spring l^6 is in the circuit by the conductor 18 with a coil of the escapement electro-magnets P, P', P², and P³ and with the spring l^8 through the metallic disk l^2 , except at one division thereof, where the insulated space l^5 breaks this electrical connection, and at the same time the circuit through the front stop, d^4 , is diverted by the contact l^6 on the disk l^2 through the spring l^{10} and the conductor 22 into the other coil of the escapement electro-magnets. At this particular subdivision of the corrector L, and for one subdivision previous thereto, the contact l^6 on the disk l^4 falls under the spring l^{11} , and the circuit through the front stop, d^4 , is closed in a parallel circuit through the springs l^{11} and l^9 and one coil of the escapement electro-magnets and the unison magnet Q during the time that the subdivision of L is passing under the springs l^9 , l^{10} , and l^{11} , and in parallel circuit through the springs l^{10} and l^{11} and the other 90 coil of the escapement electro-magnets, and also through the unison electro-magnets Q, while the succeeding subdivision of the corrector L is passing under the circuit-springs, thus 95 alternating the two impulses of the local battery B' through the escapement electro-magnet, and causing an impulse of twice the duration of one of the former impulses to energize the unison electro-magnet once in each revolution of the shaft R. The prolonged 100 closing of the tongue d against its front stop, d^4 , occurs when the brush s^3 passes three successively-closed circuit-segments on the sunflower S, and this occurs only once in each revolution of the shaft R. The unison electro-magnet Q attracts its armature q^2 and thereby 105 moves the stop q^2 out of contact with the unison-arm q^3 , secured to the shaft R, when energized by prolonged impulses. Since the prolonged impulse cannot occur unless at the 110 time when the brush s^3 is passing over the three consecutively-closed circuit-contacts in the sunflower S, the electro-magnet Q in the transmitters and receivers can release the respective unison-arms only at the unison position; and if the unison-arm q^3 of a receiver arrives at the unison position in advance of the unison-arm q^3 of a transmitter it will be 115 arrested until the unison-arm q^3 of the transmitter arrives at the unison position, when 120 both unison-arms will be simultaneously released and the type-wheels of the respective instruments will start together in unison. The alternation of impulses of the local battery B', by means of the insulation l^5 , contact l^6 , and 125 springs l^9 and l^{10} , effects a continuous rotation 130 of the type-wheel shaft R, while the relay-tongue d is in prolonged contact with its front stop, d^4 —a result impracticable when the uni-

son electro-magnet is in the same line and responds to the same impulses as the escape-movement electro-magnet.

The apparatus for shifting the double type-wheels R' and R^2 and for regulating the impressions will now be described.

The type-wheels R' and R^2 are rigidly secured to a sleeve, r , moving freely on the type-wheel shaft R . The sleeve r terminates at its lower end in a grooved collar, r' . A rod, r^6 , slides freely in the top plate, O^{10} , and the bracket O^{21} , and the arm r^4 is secured to the rod r^6 and projects at right angles therefrom, terminating in a fork with pins r^{23} , catching in the grooved collar r' . A lever, h^9 , is secured to the shaft h^{10} , supported in bearings h^8 , and the lever h^9 is pivoted at r^5 to the rod r^6 , and a shorter lever, h^7 , secured to this shaft h^{10} , projects horizontally therefrom, and at its extremity is linked a vertical bar, h^4 , pivoted at its lower end by the eyebolt h^3 , Fig. 12, to the armature-lever h of the electro-magnets H and H' . When the electro-magnet H is energized, its armature h^2 is attracted, thereby raising the levers h^7 and h^9 , and consequently the rod r^6 , arm r^4 , sleeve r , and the type-wheels R' and R^2 , to the position as shown in Fig. 2. Conversely, when the electro-magnet H' is energized and the armature h' is thereby attracted, the type-wheels R' and R^2 are lowered, so that the upper type-wheel, R' , is in the same horizontal plane previously occupied by the type-wheel R^2 , directly opposite the center of the impression-hammer g^2 , so that both type-wheels will render their impressions in the same line.

The ink-roller r^8 is long enough to supply ink to both type-wheels, and revolves freely on a pin, r^{11} , on the arm r^7 . The arm r^7 is loosely pivoted on the rod r^6 and supported on a collar, r^9 , secured to said rod r^6 . Constant pressure of the ink-roller r^8 against the type-wheels R' and R^2 is effected by the spring r^{10} , while the projecting end r^{22} of the arm r^7 impinges against an adjusting-screw, r^{12} , when the ink-roller r^8 passes over the blank spaces on the type-wheels. By this arrangement of the apparatus, as described, the ink-roller r^8 is simultaneously given the same vertical movement as the type-wheels R' and R^2 . I employ four printing-springs, two of which, r^{13} and r^{14} , are secured in the sleeve r^{17} on the stud r^{24} , and adjustable by the nut r^{20} , secured to the stud r^{21} , and the other two printing-springs, r^{15} and r^{16} , are secured in the sleeve r^{18} , and adjustable by means of the nut r^{19} on the stud r^{25} .

The printing-springs are shown in position in Fig. 3, with the type-wheels raised so as to take the impressions from the lower type-wheel, R^2 . In this position the printing-springs r^{13} and r^{15} are opposite the space between the type-wheels. When the type-wheel R' is in position for printing, the springs r^{13} and r^{15} are above this type-wheel and the springs r^{14} and r^{16} are opposite the space between the type-wheels. The printing-springs operate to pre-

vent impressions being taken from the type-wheel that is not in the same horizontal plane with the printing-hammer g^2 . The impression electro-magnet G is suspended from a curved bracket, g^5 , secured to the bracket O^4 . Its right-angular armature-lever g is pivoted at g^7 , and is extended vertically, so as to impinge against the stem g^6 of the printing-hammer g^{12} , and horizontally to carry the armature g^1 . It is adjusted by a helical spring, g^2 , and a stem, g^3 , with a milled head, g^4 . The stem g^6 of the printing-hammer g^{12} passes freely through a sleeve, g^9 , the bore of which is enlarged to receive a coiled spring, g^{10} , operating to give backward motion to the stem g^6 . When either type-wheel R' or R^2 is arrested, with a character opposite the printing-hammer g^{12} , and the electro-magnet G is energized, as hereinafter described, it will attract its armature g^1 , and the lever g , striking the stem g^6 , will force the printing-hammer against the interposed sheet of paper T^8 , causing an impression thereon of the character presented.

The paper-carriage for supporting the roll of paper T^4 and presenting it in a flat sheet, T^8 , in the rear of the type-wheels, consists, mainly, of a curved plate, T^{10} , to which are fastened the side bars, T and T' , by means of the flanges T^6 and T^7 . The paper T^8 is guided upward on this curved plate T^{10} , between the plate T^{10} and the guide-bars T^5 and T^9 . A rod, T^3 , stays the upper extremities of the bars T and T' and supports the flat sheet of paper T^8 . The paper is delivered from the roller T^4 , held in brackets on the side bars, T and T' , and is fed upward to space between lines by the feed-rollers I^3 and I^4 , revolved by the angular shaft I' . The rollers I^3 and I^4 are secured near the ends of and revolve with the shaft I' , supported in links i^{11} , pivoted at one end on studs projecting from the side bars, T and T' . The helical springs i^{12} , attached to the links i^{11} , regulate the pressure of the rollers I^3 and I^4 on the paper sheet interposed between these rollers and the feed-rollers I^3 and I^4 .

The angular shaft I' , included between the feed-rollers I^3 and I^4 , is revolved by a loose-flanged pinion, i^{19} , sliding freely on the shaft I' , and the spur-wheel i^7 , which engages in the pinion i^{19} , is fastened on one extremity of the shaft i^6 , which is held in suitable bearings secured to the back plate, O^9 . On the other extremity of the shaft i^6 is secured a ratchet-wheel, i^5 , into which engages the hook-pawl i^4 , pivoted in the extremity of the right-angular lever i^2 , which is rotated on a trunnion, i^1 . A spring, i^{17} , attached to the lever i^2 , keeps the hook-pawl i^4 in contact with the ratchet-wheel i^5 . When the type-wheels are stopped at a blank space corresponding to the key o^4 on the key-board O^2 , the electro-magnet I is thereupon energized through the local circuits hereinafter described, attracting its armature i , and thereby causing the hook-pawl i^4 to revolve the ratchet-wheel i^5 the space of one tooth, and consequently effecting a movement

of the feed-rollers I^3 and I^4 , through the intervention of the spur-wheel i^7 and flanged pinion i^{19} . The relative proportions of the lever i^2 , ratchet-wheel i^5 , spur-wheel i^7 , flanged pinion i^{19} , and feed-rollers I^3 and I^4 are such that the paper is, by one impulse through the coils of the electro-magnet I , fed upward the space between two lines at any point in the excursion of the paper-carriage. The paper-carriage moves laterally on wheels t^6 and t^8 , running between the tracks t and t' , secured to the back plate, O^9 , and on wheels t^5 and t^6 , running on the lower track, t^4 . To advance the paper-carriage, a rack, f^5 , and a counter-rack, f^7 , are employed, both attached to the bars T and T' of the carriage.

The pawl f^2 , pivoted at the extremity of the armature-lever f of the electro-magnet F , engages in the rack f^5 , and the counter-pawl f^9 , pivoted on a fixed center, f^{10} , and coupled to the stud-screw f^{14} by the link f^{13} , engages in the counter-rack f^7 when the armature-lever f is retracted by its helical spring f^3 . When the electro-magnet F is energized, attracting its armature f' , the counter-pawl f^9 is thrown away from the counter-rack f^7 . At each throw of the rack f^5 by the pawl f^2 the counter-pawl f^9 suddenly arrests the rack f^7 at the precise point required to space between two letters, while the dog f^{15} , catching in a tooth of the rack f^5 , prevents a retrograde movement thereof. The electro-magnet F is energized, as will hereinafter be more fully explained, when the type-wheel is arrested at any character or at a spacing-blank. The electro-magnet J is employed when energized to attract the armature j^2 on the short lever j' , secured to the shaft j , as shown in Figs. 1, 3, and 4. The long lever j^{13} is secured to the shaft j at a higher plane and just below the plane of the pawl j^2 , dog j^{15} , and counter-pawl j^9 . A bar, j^3 , passing under these pawls and dog, has a pin, j^4 , passing up behind the dog j^{15} , a pin, j^5 , behind the pawl j^2 , and a pin, j^6 , behind the counter-pawl j^9 , and the bar j^3 is pivoted to the extremity of the lever j^{13} . When the key o^5 is depressed and the electro-magnet J is energized, as hereinafter more fully described, and attracts its armature j^2 on the lever j' , the shaft j is slightly revolved, imparting angular motion to the long lever j^{13} and thereby causing longitudinal movement of the bar j^3 , which, by means of the pins j^4 , j^5 , and j^6 , releases the pawl f^2 and the dog f^{15} from the rack f^5 , and the counter-pawl f^9 from the counter-rack f^7 , thus permitting retrograde movement of the paper-carriage, which is solicited by the weight t^1 , hung to the cord t^{19} , passing over the pulley t^0 and attached to the arm t^{18} , secured to the paper-carriage. The key o^5 can be operated at any position of the paper-carriage to release the carriage at any point in its forward movement.

The bent arm t^2 is attached to the base O , and through the extremity of this arm passes the adjusting-screw t^3 , limiting the movement of the spring t^4 , secured to the arm t^2 . The

buffer t^8 , secured to the side bar, T , impinges against the spring t^{14} , which strikes the set-screw t^{13} , the resilience of the spring t^{14} thus neutralizing the shock, and the set-screw t^{13} limiting the retrograde movement of the paper-carriage.

To indicate by signal to the operator at a transmitter when the paper-carriage of a receiver has completed its retrograde movement, the following devices are employed: The bent lever t^{15} , Fig. 5, is pivoted at t^{26} in the bracket t^{27} , rising from the arm t^{12} . A contact, t^{22} , is insulated from the arm t^{12} by the insulation t^{24} , and a contact, t^{16} , is insulated from the bent lever t^{15} by the insulation t^{17} . The conductor 2 of the main line is attached to the contact t^{22} , and the conductor 3 of the main line is attached to the contact t^{16} . In Figs. 12 and 13 are shown the releasing-key o^5 in connection with the main-line circuit. In a cut-out circuit, 49 and 50, are placed the contact-springs o^{19} and o^{20} , with the contacts separated and the springs insulated from each other by a block of insulating material, o^{22} . From the stem o^8 of the key o^5 extends an arm, o^{21} , which impinges on the insulation o^{24} on the spring o^{19} when the key o^5 is depressed to release the paper-carriages. Since the key-board of the instrument used as a receiver is cut out of the line-circuit when the switch W is on the point w' , Fig. 13, and the key-board of the transmitter is in the circuit of the main line when the switch W is on the point w , Fig. 12, the depression of the key o^5 at the transmitter will short-circuit the portion of the line-conductors 3 and 2 between key o^5 and the contacts t^{16} and t^{22} , rendering the device for breaking the line-circuit at the contacts t^{16} and t^{22} inoperative at the transmitter. The pawl t^9 , hanging from the arm t^{10} , secured to the side bar, T , and pivoted loosely at t^{11} and stopped by the pin t^{28} , trips the bent lever t^{15} , separating the contacts t^{16} and t^{22} , when the paper-carriage recoils, thus breaking the main-line circuit in the conductors 2 and 3 at the receiver, as shown in Fig. 13. The key o^5 is an open-circuit key, and the relays D in the main line are energized, while the key o^5 is depressed, closing the main line during the retrograde movement of the paper-carriage of a transmitter and a receiver coupled in circuit, as shown in Figs. 12 and 13. The momentary interruption of this circuit by the separation of the contacts t^{16} and t^{22} when the pawl t^9 strikes the arm t^{15} allows the relay-tongues d to close the contacts d^3 against the back stops, d^4 , diverting the local circuit through the other coil of the escapement electro-magnets P , P' , P^2 , and P^3 , which permits the rotation of the type-wheels precisely the same as if the key o^5 had not been depressed. The type-wheels will again, however, be arrested when the brush s^3 arrives at the segment of the sunflower S , connected with the key o^5 . If this key has not in the meantime been released, and this revolution abnormally produced, will evidently indicate that the paper-carriage of the receiver has recoiled, thus enabling an operator to main-

tain synchronous movement of the paper-carriages of both the transmitter and receiver.

The paper-carriages of a number of receivers may be brought into unison with that of the transmitter by stopping the type-wheels at the blank for spacing between words. At each period when a blank space is made the paper-carriages will move forward a step until their forward movement is arrested. If such movement of the type-wheels be continued, any carriage that may have been retarded may be brought to the end of its forward excursion, when, by depressing the releasing-key o^5 , all the paper-carriages may be simultaneously released. The hanging pawl t^9 rides freely over the bent lever t^{15} when the paper-carriage is advanced.

In Fig. 10 is indicated the core of an electro-magnet wound overhand, with the heel end at the left and a positive current circulating in the direction indicated by the arrow therein will produce a south pole, S^3 , at the armature end. If two similarly-wound cores are connected, as is usual, and as is shown in Fig. 9, a positive current will circulate around these cores in the direction indicated by the arrows, producing a south pole, S^4 , at the heel end of the left-hand core and a north pole at the heel end of the right-hand core, and when united by a yoke in the usual manner the combined magnet will have reverse polarity at the armature end of the cores.

In Fig. 11 are shown two U electro-magnets with confronting poles, the cores of which magnets are wound with two separate coils so connected to one another and to the respective conductors that a positive current will circulate around the respective cores in the direction indicated by the lines $x' x^2$.

The helical line x' indicates the direction the positive current will circulate around the cores to produce the confronting poles S^2 and N^2 , and the line x^2 indicates the direction the positive current will circulate around the cores to produce in the confronting poles the polarity indicated by S^2 and N^2 , indicating, respectively, south and north polarity. The double coils of the electro-magnets P , P' , P^2 , and P^3 are connected in circuit, so that the currents circulate as indicated by the line $x' x^2$ in Fig. 11.

The operation of the electro-magnets and mechanical devices and the course of the electrical circuits in a transmitter and a receiver when the switch W is turned to the point w , as in Fig. 12, and the switch W is turned to w' , as in Fig. 13, will now be described. Since the transmitters and receivers are similar in every respect, and can be operated interchangeably by reversing the position of the switches W , similar letters and figures have accordingly been employed to designate similar devices and circuits in Figs. 12 and 13.

In Fig. 13 the conductor 8 is broken at w , the switch W cutting out of circuit the contact-springs o^{12} and o^{16} and segments of the sunflower S , while in Fig. 12 the conductor 3 is broken

at w' , and the segments of the sunflower S and the contact-springs o^{12} and o^{16} are in circuit. The relay-magnets D in both instruments respond simultaneously to all impulses in the main line, and all other magnets in both instruments respond similarly to simultaneous impulses of the local batteries when their circuits are closed through the relay tongues and by either the director or corrector.

It will of course be understood that the magnetic devices and circuits in both instruments will operate simultaneously, and hence the description of their operation hereinafter given refers to both the transmitting and receiving instruments.

The type-wheel shafts R and the brushes s^3 revolve to the left, as indicated by the arrows. Starting with the brush s^3 of the transmitter, Fig. 12, arrested on a closed-circuit contact—that is, the first segment marked s^7 in its path and direction of rotation—and assuming that the closed-circuit spring o^{16} has been depressed by its key o' interrupting the line-circuit at the anvil-bar o^{14} , the main-line circuit may be followed from earth at A , Fig. 12, by the conductor I to the negative electrode of the battery B , from the positive electrode by the conductor 2 to the contact t^{22} , thence by the contact t^{16} and the conductors 3 and 4 to the anvil-bar o^{13} , and by the conductor 5 to the anvil-bar o^{14} . The main-line circuit is broken at the anvil-bars o^{13} and at the sunflower-segments s^8 , connected to the springs o^{12} , until a key, o , is depressed to cause a spring, o^{12} , to make a contact with the anvil-bar o^{13} and the brush s^3 is over a corresponding segment, s^8 . The circuit is normally closed at the contact-springs o^{16} through any segment s^7 over which the brush s^3 passes; but it has been assumed that the key o' has been depressed and the brush s^3 is over the first segment marked s^7 , connected to spring o^{16} , and consequently the main-line circuit is interrupted at both ends of the conductor 7 , attached to the springs o^{16} and the segment s^7 .

The circuit continues from the contact-spring o^{16} by the conductor 7 , segment s^7 , brush s^3 , arm s^2 , hub s' , spring s^4 , and the conductor 8 to the point w , and by switch W and conductor 9 to the coil of the relay D , through the same and conductor 10 to the coil of relay D in Fig. 13, and by the conductor 9 , switch W , point w , and conductor 3 to the contacts t^{16} and t^{22} , thence by the conductor 2 to earth at A . The circuit being interrupted at the anvil-bar o^{14} , the tongues of the relays D are against their back stops, d^5 , and the circuits of the local batteries B' are completed from the positive electrodes of the batteries B' through the conductors 11 , relay-tongues d , back stops, d^5 , and conductors 12 to one of the coils of the electro-magnets P^2 , conductors 19 , coils of electro-magnets P^3 , connections 13 , coils of electro-magnets P' , connections 36 , coils of electro-magnets P , and by the conductors 14 and 16 to the negative electrodes of the batteries B' . The local circuits being thus closed, the electro-magnets in circuit are energized by the

positive current in one of the two parallel coils attracting the polarized armatures p to the poles of, say, P and P' , the pawls p^4 engaging in a tooth of the scape-wheels p^5 , and arresting the type-wheel shafts R and the correctors L one step back of the position shown in Figs. 12 and 13. The springs r^6 therefore rest on the metallic portion of the disks r^6 . If the key o' be released, the main-line circuit 10 just described will be closed by the spring o^{16} impinging on the anvil-bar o^{14} , the relays D will be energized, attracting their armatures d' , and the local circuits will be closed from the positive electrodes of the batteries B' , in a 15 manner as already described, through the relay-tongues d , thence through the front stops, d^4 , conductors 17, springs l^8 , sleeves l' , disks l^6 , springs l^6 , (still resting on the metallic disks l^6), conductors 18, the other parallel coils of 20 electro-magnets P^3 , connections 35, parallel coils of the electro-magnets P^2 , connections 20, parallel coils of P , connections 51, parallel coils P' , and by the conductors 21, 15, and 16 to the negative poles of the batteries B' . The 25 electro-magnets P , P' , P^2 , and P^3 , in circuit, being energized by a positive current through the second parallel coils now in circuit, (the first coil being in the circuits interrupted at the back stops, d^6), the confronting poles are thereby reversed and the polarized armatures p are 30 attracted to the poles of the electro-magnets P^2 and P^3 , releasing the pallets p^4 and causing the pallets p^3 to engage in the next adjacent tooth of the scape-wheels p^5 , thus permitting 35 the type-wheel shafts R to advance one thirty-second of a revolution by the action of the coiled springs v^8 . The brush s^3 of the transmitter will now rest on the second segment s^7 , still in connection, by the conductor 7, in a 40 closed circuit of the main line, as previously described, and the relay-tongues d still remain in contact with their front stops, d^4 ; but the local circuits of the batteries B' are now reversed by the correctors L , the circuit being 45 from the front stops, d^4 , through the conductors 17, springs l^6 , sleeves l' , contacts l^6 of the disks l^6 , (springs l^6 and conductors 18 being cut out of circuit by the insulating-spaces l^6), springs l^{10} and conductors 22 to a junction with 50 the conductors 12, the circuit of which is now interrupted at the back stops, d^6 , thence, by a portion of the conductors 12, to the electro-magnets P^2 , thence through the coils of the electro-magnets P^2 , P' , and P , and connections 55 19, 13, and 36, and by the conductors 14 and 16 to the batteries B' . The polarized armatures p are again attracted to the poles of the electro-magnets P and P' , and the type-wheel shafts R move another thirty-second of a revolution, throwing the brush s^3 on the third segment marked s^8 , which being in a closed circuit, the relay-tongues d still remain against the front stops, d^4 ; but, the correctors L having 60 moved one division, the last-described local circuit is closed through the front stops, d^4 , conductors 17, springs l^6 , sleeves l' , metallic disks l^6 , springs l^6 , and conductors 18, &c., as pre-

viously described, and the polarized armatures are again attracted to the poles of electro-magnets P^2 and P^3 , releasing the pawls p^4 and the 70 type-wheel shafts R , and the brush s^3 of the transmitter advances another step, as before mentioned, which throws the brush s^3 on an open-circuit segment, s^9 , of the sunflower S ; and since all remaining segments are alternately open and closed circuit contacts, the 75 type-wheel shafts R , solicited by the springs v^8 , will continue to revolve step by step as the scape-wheels p^5 are released by the vibration of the polarized armatures p until arrested by the connection of two consecutive open or closed circuit segments of the sunflower S , produced by the depression of a key, o' or o .

In the first two positions of the correctors 85 L , hereinbefore described, while the brush s^3 was on two consecutive segments s^7 , s^8 and the current was prolonged through the front stops, d^4 , of the relays D , the branch circuits of the batteries B' were completed from the sleeves 90 l' , through the contacts l^6 on the disks l^6 , springs l^6 , conductors 23, the coils of electro-magnets Q and conductors 24, 15, and 16 to the negative electrodes of the batteries B' , and the electro-magnets Q were energized by a pulsation in 95 duration equal to two pulsations through the electro-magnets P , P' , P^2 , and P^3 , attracting their armatures q and withdrawing their arms q^2 clear of the unison-arms q^3 without checking the type-wheels. Since such prolonged 100 pulsations in the circuit of the electro-magnet Q in a receiver can occur only when the brush s^3 is passing the first two segments s^7 in a transmitter, it is evident that if the type-wheels R' and R^2 of the instruments are not in unison 105 the unison-arm of the receiver will be arrested at the unison position until the brush s^3 of the transmitter passes over the second segment s^8 , when an impulse of double the duration will simultaneously release the unison-arms q^3 of 110 both the transmitter and receiver, and the type-wheels R' and R^2 of both instruments will again revolve in unison.

Continuous rotation of the type-wheels R' and R^2 is maintained during the continuation 115 of the impulses over the main line, as already described, by the force of the springs v^8 , which are wound by the electromotors C . The motors C are in the circuits of the batteries B' in both transmitter and receivers, or they may be, 120 if so desired, in the circuits of independent batteries. The circuits originating at the positive electrodes of the batteries B' are by conductors 25 to one of the field-magnet coils, thence to the opposite field-magnet coils, 125 thence by the conductors 26 to the brushes c^2 , through the coils of the armatures c to the brushes c^3 , thence by the conductors 27 to the springs v^{18} , Fig. 4, through the springs v^{18} and the insulated metallic disks v^{20} , springs v^{21} , and 130 by the conductors 52 and 16 to the negative electrodes of the batteries B' . When the springs v^8 are wound up to a certain tension, the inclined surface of the cams v^{16} lift the

pins v^{19} , made of insulating material, raising the springs v^{21} out of contact with the metallic disks v^{20} , and the circuit just described being thereby temporarily interrupted, the motors C 5 are stopped, or otherwise they may be arrested by the Geneva-stop pinions v^{15} locking in the stop-wheels v^{10} .

The line-circuits of the batteries B and also the local circuits of the batteries B', which operate the motors C and the escapement and unison electro-magnets P, P', P², P³, and Q, act in the manner already described to control the type-wheels R' and R². In the operations of printing, of moving the type-wheels, and of feeding and releasing the paper-carriages the circuits from the auxiliary batteries B² may be employed. The circuits through the dotted conductors 46, 47, 48, and 32 are in this case to be considered as disconnected or inoperative. When any character-key o is depressed, a segment, s^8 , following a closed-circuit segment s^7 , will be placed in a closed circuit through the conductor 6, and when the brush s^3 is in contact with this segment the tongues 15 of the relays D will be held against their front stops, the consecutive order of makes and breaks over the line having been interrupted by closing the circuit at the anvil-bar o^{13} and the spring o^{12} by the open-circuit key o. The 20 type-wheels R' and R² will therefore be arrested with a character corresponding with the character on the particular key o which has been depressed and facing the paper T⁸ directly opposite the printing-hammers g^{12} . 25 When any character on the type-wheels, or the blank space thereon for spacing between words, is presented to the printing-hammers, the directors M are in such relative angular position that the circuits from the batteries B', 30 which are permanently in closed circuits from the positive electrodes through the conductors 28 and 45 to the springs m^{10} , sleeves m' , Figs. 12, 13, 7, and 7^a, and conductors 28 and 33 to the springs m^{17} and the sleeves m^8 , will be 35 completed from the sleeves m' and m^8 , through the springs m^{11} or springs m^{16} , according as the printing-contacts m^{38} on the disks m^2 or the printing-contacts m^{45} on the disks m^7 are under these springs in both the transmitter and 40 receivers.

In Fig. 7 contact m^{38} falls under a spring, m^{11} , and the circuit continues from the sleeves m' , disks m^2 , contacts m^{38} , springs m^{11} , conductors 45 29, coils of the electro-magnets F, conductors 30, coils of the electro-magnets G in both instruments, and to the negative electrodes of the batteries B² by the conductors 31 32, and the electro-magnets F consequently attract their armatures f^7 , causing the pawls f^2 to engage in the 55 next adjacent tooth, respectively, of the racks f^6 , while the counter-pawls are, by the action of the links f^{13} , thrown out of contact with the counter-racks f^7 of both transmitter and receiver. The electro-magnets G, being energized, attract their armatures g' , and the extremities of their levers g consequently strike the stems g^6 , forcing the printing-hammers g^{12}

against the paper T⁸, and effecting thereon simultaneous impressions of the character presented. When the open-circuit key o is released, the circuit through the segment and brush is interrupted at an anvil-bar, o^{13} , and spring o^{12} , and the relay-tongues d fall against their back stops, d^5 , permitting motion of the scape-wheels p^5 , and the directors M consequently interrupt at the contacts m^{38} the circuits just described through the electro-magnets F and G. The armatures g' are therefore withdrawn by their retracting-springs g^2 , and the printing-hammers g^{12} are withdrawn 75 by the helical springs g^{10} , encircling the stems g^6 . The armatures f' are withdrawn by the retracting-springs f^3 , attached to the levers f , which, by their pawls f^2 , engaging in the racks f^5 , move the paper-carriages to space simultaneously between two letters, while the counter-pawls f^9 , engaging in the counter-racks f^7 , limit the movement of the paper-carriages. The type-wheels R' and R² continue to revolve, and the contacts m^{38} and m^{45} being 80 short, the momentary closing of the circuits through the electro-magnets F and G is not of sufficient duration to energize these electro-magnets so as to attract their armatures. If a key, o', is depressed, a segment, s^8 , connected to an open-circuit spring, o^{12} , will be succeeded by a segment, s^7 , the circuit to which, through the conductor 7, will be interrupted at the anvil-bar o^{14} and spring o^{16} , and, the relay-tongues d remaining against 85 their back stops, d^5 , the brush s^3 will be arrested over the segment s^7 in connection, by a conductor, 7, with the particular key o' depressed. The relay-tongues being thus arrested on their back stops, d^5 , a character on the 90 type-wheels corresponding with the key o' depressed will be presented to the printing-hammers g^{12} , as hereinbefore described; but the local circuits of the batteries B² will now pass from the directors M, by the sleeves m' , contacts m^{45} on the disks m^7 , springs m^{16} , and conductors 95 34 to the electro-magnets F, and by the conductors 30 to the electro-magnets G, thence, as previously described, to the negative electrodes of the batteries B², while the 100 springs m will rest on insulating-spaces m^{49} on the disks m^2 , thus interrupting the circuits 105 through the springs m^{11} and the conductors 29. Another impression will consequently be 110 made, and upon releasing the key o' the circuit of the main line will be closed through the spring o^{16} and anvil-bar o^{14} , and the type-wheels will again be rotated, as hereinbefore 115 mentioned.

To elevate the type-wheels, as shown in the 120 position indicated in Fig. 2, the key o^3 , which is an open-circuit key, is depressed, closing the circuit at the anvil-bar o^{13} by the springs o^{12} . The type-wheels are arrested with the blank spaces on both the type-wheels R' and R² opposite the paper T⁸, and the local circuits of the batteries B² are closed by the directors M from the sleeves m' , through the disks m^3 , contacts m^{41} , springs m^{12} , conductors 37, and 125 130

the coils of the electro-magnets H, thence by the conductors 38 and 32 to the negative electrodes of the batteries B², while all the springs m¹¹, m¹³, m¹⁴, m¹⁵, and m¹⁶ bear on insulating material on the peripheries of their respective disks. The electro-magnets H will alone be energized, attracting their armatures h¹, and elevating vertically the bars h¹, which rock the shafts h¹⁰ by means of the levers h¹, elevating 5 the extremities of the levers h¹, which control the movements of the rods r⁶, carrying the forked arms r⁴, provided with pins r²³, which engage in the grooves r¹ of the sleeves r, carrying the type-wheels R' and R². The ink- 10 rollers r⁸ are carried on the arms r⁷, supported by the collars r⁹ on the rods r⁶, and consequently the ink-rollers r⁸ move in a vertical direction with the type-wheels. Upon releasing the key o³ the type-wheels R² revolve in 15 position to give impressions, and the springs r¹³, r¹⁴, r¹⁵, and r¹⁶ prevent impressions being made by the type-wheels R'. To lower the 20 type-wheels, so that impressions may be taken from R', the key o², which is a closed-circuit key, is pressed, breaking the circuit at the anvil-bar o¹⁴ and spring o¹⁶ of a closed-circuit key. The type-wheels are arrested with another blank space corresponding to the key o², facing the paper T⁸, and the circuits of the 25 local batteries B² are completed through the directors M by the contacts m¹⁴ through the springs m¹⁵, conductors 39, coils of the electro-magnets H', and conductors 40 and 32 to the negative electrodes of the batteries B², energizing the electro-magnets H', and thereby attracting their armatures h¹, which draw down 30 the bars h¹ and lower the type-wheels and ink-rollers, so that the type-wheels R' will be in the same horizontal planes as the printing-hammers g¹². Releasing the key o² causes the 35 type-wheels to continue to revolve until stopped by the depression of another key.

To space between lines at any point in the excursion of the paper-carriage, the key o⁴ is 40 pressed, whereupon the type-wheels are arrested with a corresponding space presented to the paper T⁸, and the local circuits of the batteries B² are closed through the directors M, contacts m¹² on the disks m⁴, springs m¹³, 45 conductors 41, coils of the electro-magnets I, and conductors 42 and 32 to the negative electrodes of the batteries B² in the transmitters and receivers, thereby energizing the electro-magnets I, which attract their armatures i¹, 50 revolving the bent levers i² on their trunnions i³, and causing the hook-pawls i⁴ to revolve the ratchet-wheels i⁵ one notch.

The ratchet-wheels i⁵ are secured to the shafts i⁶, which carry spur-wheels i⁷, engaging 55 in flanged pinions i⁸, moving loosely in a longitudinal direction on the angular shafts I', which carry on their extremities short feed-rollers I³ and I⁴, pressing against the under side of the paper T⁸, while the rollers I⁵ and I⁶ 60 bear on the paper over the rollers I³ and I⁴ and are drawn downward by the springs i⁹, and therefore it follows that the rotation of

the ratchet-wheels i⁵ the space of one notch in each will, by proper proportion of the gear-wheels and feed-rollers, cause the paper to be 70 fed upward the desired space between two lines. When the key o⁴ is released, the circuits through the electro-magnets I are interrupted by the movement of the directors M, and the retracting-springs i¹⁰ withdraw the armatures i¹, throwing forward the bent levers i², and causing the hook-pawls i⁴, held in contact with the ratchet-wheels i⁵ by their springs i¹¹, 75 to engage in another tooth in each of the ratchet-wheels. 80

To release the pawls f² and dogs f¹⁵ from the racks f⁵ and the counter-pawls f⁹ from the racks f⁷, the key o⁵ must be depressed. Corresponding with this key there is a blank on the type-wheels R' and R², and when they are 85 arrested with the blank opposite the printing-hammers g¹² the circuits of the local batteries B² are closed by the directors M, through the contacts m¹³ on the disks m⁵, springs m¹¹, conductors 43, the coils of the electro-magnets J, 90 and conductors 44 and 32 to the negative electrodes of the batteries B². The electro-magnets J are thereby energized, attracting their armatures j¹, attached to the lever j², drawing forward the bars j³, and causing the pins j⁴, j⁵, 95 and j⁶ to release the pawls f² and dogs f¹⁵ from the racks f⁵ and the counter-pawls f⁹ from the counter-racks f⁷ of the respective carriages. The paper-carriages thereupon are free to move backward, solicited by the cords t⁹ and 100 weight t¹¹. When the hanging pawls t⁹ strike the bent levers t¹⁰, the main-line circuit is interrupted between the contacts t¹¹ and t¹² of a receiver, and the type-wheels of the respective instruments make one revolution, as herein-before described, thereby signaling the completion of the retrograde movement of the 105 respective paper-carriages.

In the local circuits of the batteries B² the conductors 46, 47, and 48 were excluded. If 110 the conductors 28, 33, and 45 from the negative electrodes of the batteries B², Figs. 12 and 13, to the springs m¹⁰ and m¹⁷ be omitted, and the conductors 46 from the positive electrodes of the batteries B² be connected through the 115 conductors 16 to the negative electrodes of the batteries B', the batteries B² and B' will be combined, and if the positive electrodes of the batteries B' be connected to the springs m¹⁰ by the 120 conductors 47, and the springs m¹⁷ by the 125 conductors 47 and 48, the respective circuits of the electro-magnets F, G, H, H', I, and J will be closed whenever closed by the directors M in parallel circuits with the circuits of the electro-magnets P, P', P², and P³, and parallel with the circuits through the electro-magnets Q whenever their circuits are closed by the correctors L.

I do not limit myself to any specific disposition of the local batteries and circuits, since it 130 will be obvious to those skilled in electrical science that separate or combined batteries may be employed with the director M and corrector L to produce the desired result; nor

do I limit myself to the use of three successive closed-circuit segments in a sunflower, the other segments of which are alternately connected in open and closed circuits of the main line, as these are unnecessary, and all the segments may be alternately connected in open and closed circuits except when employed in connection with the unison electro-magnet Q, responding to prolonged impulses.

10 I contemplate using printing and ratchet electro-magnets responding to prolonged pulsations in the same circuit with the escapement electro-magnets without the intervention of a circuit-director.

15 Having thus described the nature and objects of my invention, what I claim as new, and desire to secure by Letters Patent, is—

1. The combination of a line battery and circuit, a sunflower having segmental contacts alternately in open and closed circuits with contact-springs, a type-wheel shaft and motive power for rotating the same, a brush secured to and insulated from said type-wheel shaft and traversing said segmental contacts, a relay electro-magnet in said circuit and its armature-lever provided with double contact-points, front and back stops on which said contact-points impinge, parallel-coil-neutral-escapement electro-magnets and a polarized armature controlled thereby, a local-battery circuit closed by said relay alternately through the parallel coils of said electro-magnets in reverse direction from the same electrode of said battery, said polarized armature carrying pallets, and a scape-wheel on said type-wheel shaft controlled thereby, substantially as and for the purposes set forth.

2. The combination of a line battery and circuit, a sunflower with contacts alternately in open and closed circuits of said line, a type-wheel shaft, an electromotor for winding a coiled spring for rotating said shaft, a brush secured to and insulated from said type-wheel shaft, a double-point relay with its coils in said circuit, double neutral-escapement electro-magnets wound with parallel coils and a polarized armature controlled thereby, and a local battery circuit alternately closed by said relay through parallel coils of said escapement electro-magnets in reverse direction from the same electrode of said local battery, said polarized armature carrying pallets controlling a scape-wheel secured to said type-wheel shaft, substantially as and for the purposes set forth.

3. The combination of a main-line battery and circuit-keys with open and closed contact-springs in the circuit of said battery, a sunflower with contacts electrically connected alternately in open and closed circuits with said contact-springs, a brush for traversing said contacts, a type-wheel shaft and motive power for actuating said shaft, a double-point relay in said main-line circuit, a local-battery circuit and neutral-escapement electro-magnets wound with parallel coils included therein, a polarized armature controlled thereby, said double-point relay closing the circuit through

the same electrode of the local battery alternately in reverse direction through the parallel coils of said escapement electro-magnets, 70 the polarized armature carrying pallets, a scape-wheel on said type-wheel shaft controlled by said polarized armature, and printing and ratchet electro-magnets with their armatures, levers, and retracting-springs, said 75 electro-magnets energized, respectively, by the circuit of said local battery, substantially as and for the purposes set forth.

4. The combination, substantially as hereinbefore set forth, of a main-line battery and 80 circuit, keys with open and closed contact-springs in the circuit of said battery, a sunflower with segmental contacts electrically connected alternately in open and closed circuits with said contact-springs, a brush traversing said contacts, a type-wheel shaft and motive power for actuating said shaft, two 85 type-wheels secured to a sleeve on said shaft, a double-point relay in said circuit, a local-battery circuit, neutral-escapement electro-magnets included therein, a polarized armature controlled thereby, a circuit-director on 90 said type-wheel shaft, springs bearing on the hubs and the disks carrying insulations and contacts for closing the circuit of said battery, 95 two independent electro-magnets in separate circuits connected with two of the disks of said director, and their hinged armatures, lever, shaft, and lever-arms for raising and lowering said type-wheels.

5. The combination of a main-line battery-circuit, keys with open and closed contact-springs in the circuit of said battery, a sunflower with contacts electrically connected alternately in open and closed circuits with 100 said contact-springs, a type-wheel shaft and motive power and devices for rotating the same, two type-wheels secured to a loose sleeve thereon, a double-point relay in said circuit, a local-battery circuit, neutral-escapement 105 electro-magnets therein, a polarized armature controlled thereby, a circuit-director secured to said type-wheel shaft, springs bearing on the hubs and respective disks of said director, carrying insulations and contacts for closing 110 the circuits of said battery, two independent electro-magnets in separate circuits with said director, said electro-magnets, with their hinged lever, armature, shaft, and lever-arms, operating to shift said type-wheels, and ratchet 115 and printing electro-magnets with their armatures, levers, and retracting-springs, said electro-magnets energized by impulses in the circuit of said local battery, substantially as and for the purposes set forth.

6. The combination, substantially as hereinbefore set forth, of a line-battery circuit, keys with open and closed contact-springs in the circuit of said battery, a sunflower with contacts electrically connected alternately in open 120 and closed circuits with said contact-springs, a type-wheel shaft and motive power for rotating the same, a double-point relay in said circuit, a local-battery circuit, neutral-escapement 125

ment electro-magnets included therein, a polarized armature controlled thereby, a circuit-director secured to said type-wheel shaft, springs bearing on the hubs and the disks carrying insulations and contacts for closing the circuits of said battery, ratchet and printing electro-magnets with their armatures, levers, and retracting-springs, a feeding electro-magnet in the local circuit closed by said director, 5 its armature, lever, pawls, ratchet-wheel, shaft, spur-wheel, and gear-wheels, a paper-carriage carrying an angular shaft with feed-rollers on its extremities, and a flanged pinion moving on said shaft between said rollers and 10 engaging in said spur-wheel and operating to feed the paper to space between lines at any point in the excursion of the paper-carriage.

7. The combination of a line-battery, keys with open and closed contact-springs in the circuit of said battery, a sunflower with contacts electrically connected alternately in open and closed circuits with said contact-springs, a type-wheel shaft, a motor for winding a coiled spring for imparting motion to said shaft, two 15 type-wheels secured to a loose sleeve thereon, a double-point relay in said line-circuit, a local-battery circuit and neutral-escapement electro-magnets wound with parallel coils included therein, and a polarized armature, a scape-wheel secured to said type-wheel shaft and controlled by said polarized armature, two independent electro-magnets and their actuating devices, electrical devices, substantially as described, for closing the circuits, ratchet and 20 printing electro-magnets included in a local circuit and their actuating devices, a feeding electro-magnet and its actuating devices, a paper-carriage carrying an angular shaft with feed-rollers on its extremities, and a flanged 25 pinion moving on said shaft between said rollers and engaging in a spur-wheel, substantially as and for the purposes set forth.

8. The combination, substantially as hereinbefore set forth, of a line-battery circuit, 45 keys with open and closed contact-springs in the circuit of said battery, a sunflower with contacts electrically connected alternately in open and closed circuits with said contact-springs, a type-wheel shaft, motive power for 50 winding a coiled spring for rotating said shaft, a double-point relay in said circuit, a local-battery circuit and neutral-escapement electro-magnets wound with parallel coils therein, a polarized armature, ratchet and printing 55 electro-magnets included in the local circuit, a feeding electro-magnet and its actuating devices, electrical devices for closing the circuits through said electro-magnets, a paper-carriage carrying an angular shaft with feed-rollers on 60 its extremities, a flanged pinion moving on said shaft between said rollers and engaging in a spur-wheel, a rack and counter-rack, and a releasing electro-magnet with its actuating devices, operating to release the paper-carriage 65 at any point in its excursion.

9. The combination of a line-battery circuit, keys with open and closed contact-springs in

the circuit of said battery, a sunflower, substantially as described, a type-wheel shaft, motive power for rotating the same, two type-wheels on a loose sleeve thereon, a double-point relay in said line-circuit, a local-battery circuit and neutral-escapement electro-magnets wound with parallel coils therein, and a polarized armature, a scape-wheel on said shaft, 70 two independent electro-magnets and their actuating devices, electrical devices for closing the circuit through said electro-magnets, ratchet and printing electro-magnets in a local circuit, their actuating devices, a feeding electro-magnet and its actuating devices, a paper-carriage carrying an angular shaft with feed-rollers on its extremities, a flanged pinion moving on said shaft between said rollers and engaging in said spur-wheel, a rack and counter-rack, and a releasing electro-magnet in the 75 same circuit and its actuating devices, substantially as and for the purposes set forth.

10. The combination, substantially as hereinbefore set forth, of a type-wheel shaft, suitable motive power for actuating the same, means for arresting said type-wheel shaft, double type-wheels secured to a loose sleeve thereon, a battery-circuit and two independent electro-magnets included therein, their 90 actuating devices for shifting the sleeve, and electrical devices for closing the circuit through said electro-magnets to raise and lower the type-wheels.

11. The combination with a double-point relay in a main-battery circuit and electrical devices for sending impulses through said circuit, neutral-escapement electro-magnets wound with parallel coils in a local circuit, and a polarized armature controlled thereby, 100 of a type-wheel shaft, a power for rotating the same, double type-wheels on a loose sleeve thereon, a local-battery circuit, two independent electro-magnets with their actuating devices, printing and ratchet electro-magnets in 105 said local circuit and their actuating devices, and electrical devices operated by the type-wheel shaft for directing the circuits through said electro-magnets, substantially as and for the purposes set forth.

12. The combination, with a type-wheel shaft, motive power for actuating the same, a circuit-director thereon, springs bearing on hubs, and disks carrying insulations and contacts, of a local-battery circuit, a feeding electro-magnet 120 with its actuating devices, a paper-carriage carrying an angular shaft and feed-rollers on its extremities, a flanged pinion moving on said shaft between the rollers and engaging in a spur-wheel, and printing and ratchet electro-magnets in said local circuit and their 125 actuating devices, substantially as and for the purposes set forth.

13. The combination, with a local-battery circuit and feeding and releasing electro-magnets therein and their actuating devices, of a paper-carriage carrying an angular shaft and feed-rollers on its extremities, a flanged pinion moving on said shaft between the rollers

and engaging in a spur-wheel, a rack and counter-rack, pawls, dogs, and counter-pawls, printing and ratchet electro-magnets in said local circuit and their actuating devices, a 5 type-wheel shaft and a force for rotating the same, means, substantially as described, for arresting said shaft, and a circuit-director, substantially as and for the purposes set forth.

14. The combination, with a circuit-director, 10 a type-wheel shaft, a force for impelling it, a double-point relay, a main-line battery-circuit, a local-battery circuit and neutral-escapement electro-magnets wound with parallel coils therein and a polarized armature controlled thereby, circuit-keys, and a sunflower, substantially as described, of printing and ratchet electro-magnets with their actuating devices, a paper-carriage carrying an angular shaft and feed-rollers on its extremities, a flanged pinion moving on said shaft between the rollers and engaging in a spur-wheel, a rack and counter-rack, and feeding and releasing electro-magnets in said local circuit and their actuating devices, substantially as and for the purposes set forth. 25

15. The combination, with a circuit-corrector, a type-wheel shaft, motive power for actuating same, a line-battery circuit, a double-point relay in said circuit, a local-battery 30 circuit and neutral-escapement electro-magnets wound with parallel coils therein, a polarized armature controlled thereby, circuit-keys, and a sunflower, as described, of a unison electro-magnet and its actuating devices, substantially as and for the purposes set forth.

16. The combination, with a line-battery circuit, keys with open and closed contact-springs in the circuit of said battery, a sunflower with three successive contacts connected to closed-circuit springs, and an insulated brush on the type-wheel shaft connected with said line and traversing said insulated contacts, causing a prolonged closed circuit in the line once in each revolution of the type-wheel, of a double-point 45 relay included in said line responding to makes and breaks of circuit, a local-battery circuit, neutral-escapement electro-magnets with parallel coils in a local-battery circuit, a polarized armature, a unison electro-magnet with its armature, lever, and stop, and circuit-correcting devices, substantially as and for the purposes set forth.

17. The combination, with a line-battery circuit, keys with open and closed contact-springs 55 in the circuit of said battery, a sunflower, substantially as described, with three successive segments connected to closed-circuit springs, and an insulated contact-brush, of a double-point relay in said line, a type-wheel shaft and a force for rotating the same, a local-battery circuit, neutral-escapement electro-magnets therein, and a polarized armature, circuit directing and correcting devices secured to said shaft, and a unison electro-magnet with its 60 actuating devices, substantially as and for the purposes set forth.

18. The combination, with a line-battery cir-

cuit, a sunflower, and circuit-keys, substantially as described, an insulated brush traversing said sunflower-segments, a type-wheel 70 shaft and means for actuating the same, and circuit directing and correcting devices secured thereon, of a double-point relay in said line-circuit, a local-battery circuit and neutral-escapement electro-magnets therein, a polarized armature, a scape-wheel secured to said shaft, printing and ratchet electro-magnets in said local circuit and their actuating devices, and a unison electro-magnet with its actuating devices, substantially as and for the purposes 80 set forth.

19. In combination with a line-battery circuit, a sunflower, and circuit-keys arranged and operating substantially as described, an insulated brush traversing the segments of the 85 sunflower, a type-wheel shaft and a motor for actuating a coiled spring for rotating said shaft, means for arresting the same, circuit directing and correcting devices secured to said shaft, a double-point relay in the line-circuit, neutral-escapement electro-magnets wound with parallel coils in a local-battery circuit, a polarized armature, ratchet and printing electro-magnets in said line-circuit and their actuating devices, a paper-carriage 95 and means, substantially such as described, for actuating the same, feeding and releasing electro-magnets with their actuating devices, and a unison electro-magnet with its armature, lever, retracting-spring, and stop, substantially as and for the purposes set forth. 100

20. The combination, with a line-battery circuit, a sunflower, and circuit-keys arranged and operating substantially as described, an insulated brush, a type-wheel shaft, motive power for actuating the same, means for arresting said shaft, two type-wheels on a loose sleeve thereon, and circuit directing and correcting devices secured to said shaft, of a double-point relay in said line-circuit, a local-battery circuit and neutral-escapement electro-magnets therein, a polarized armature controlled thereby, a scape-wheel on the type-wheel shaft, a unison electro-magnet in said local circuit and its actuating devices, two independent electro-magnets in the same circuit and their actuating devices, the printing and ratchet electro-magnets, the feeding and releasing electro-magnets, and a paper-carriage and means, as described, for advancing and for releasing the same, substantially as and for the purposes set forth. 115

21. The combination of a type-wheel shaft, a loose sleeve thereon, two type-wheels secured to said sleeve, a vertical sliding bar, a bifurcated arm secured to said sliding bar and engaging in said sleeve, means for elevating said bar and sleeve, collars on said sliding bar, a horizontal lever loosely pivoted to said bar between said collars and carrying an ink-roller, a spring pressing against said horizontal lever, and a stop for limiting its movement, substantially as and for the purposes set forth. 125 130

22. The combination of the top plate, the

vertical stud-pins, studs, and the adjustable sleeves, and the double springs attached, respectively, thereto, substantially as and for the purposes set forth.

5 23. The combination, with a type-wheel shaft, a sleeve thereon, type-wheels secured thereto, and means for shifting the same, of a top plate, stud-pins and studs, sleeves adjustable theron, springs attached thereto and so arranged as to vibrate above or below and between said type-wheels, a paper-carriage for presenting a sheet of paper thereto, a printing electro-magnet with its actuating devices, and a hammer operated thereby, substantially as and for the purposes set forth.

24. In a page-printing telegraph, the combination of a shaft, double type-wheels secured to a sleeve movable on said shaft, a vertical shifting rod carrying a rigid arm engaging in said sleeve, a pivoted arm supported by said sliding rod and carrying an ink-roller, a spring bearing against said sliding rod, and means, as described, for shifting by a positive simultaneous movement without the aid of friction said ink-roller and type-wheels, whereby said type-wheels are also alternately brought into the same plane with the printing-hammer and printing-springs, substantially as described, for permitting impressions being recorded from either type-wheel in the same continuous line.

25. The combination, substantially as hereinbefore set forth, of a type-wheel shaft and means for limiting the step-by-step movement thereof, a drum with a spur-wheel secured thereto, a pinion on the type-wheel shaft, a drum-shaft and a coiled spring interposed between said drum and its shaft, a local-battery circuit, an electromotor included therein operating continuously or intermittently to wind said spring, a ratchet on the shaft of said drum, and a pawl to prevent its retrograde movement.

26. The combination, with a Geneva stop, substantially as shown and described, of a type-wheel shaft and means for limiting its step-by-step movement, a pinion on the type-wheel shaft, a drum and a spur-wheel secured thereto, a drum-shaft and a spring interposed between the drum and its shaft, a local-battery circuit, an electromotor, intermediary gearing, a ratchet on said shaft, and a pawl to prevent its retrograde movement.

27. The combination, with a type-wheel shaft and means for limiting the step-by-step movement thereof, a pinion on said type-wheel shaft, a drum and a spur-wheel secured thereto, a drum-shaft and a coiled spring interposed between said drum and its shaft, a local-battery circuit, an electromotor in said circuit, a ratchet on said shaft, and a pawl to prevent its retrograde movement, of a Geneva stop actuated by said drum-shaft, an insulated metallic disk on said shaft, circuit-springs bearing on said disk, a pin of insulating material moving freely therein beneath one of said springs, a stop and a cam secured thereto, substantially as and for the purposes set forth.

28. The combination, with a local-battery

circuit, a drum, and a motor for constantly or periodically winding a spring within said drum, of a type-wheel shaft, neutral-escape-
70
ment electro-magnets wound with parallel coils in said local circuit, a polarized armature controlled thereby, a line-battery circuit, and a double-point relay responding to impulses in said line-circuit produced automatically 75 through circuit-interrupting devices operating through the movement of said shaft, substantially as and for the purposes set forth.

29. The combination, with a type-wheel shaft and type-wheels on a loose sleeve thereon, two independent electro-magnets and their actuating devices for shifting the same, and means, substantially as described, for holding the ink-
80
roller and shifting it with the type-wheels, of stud-pins secured to the top plate, sleeves ad-
85
justed thereto, and springs between and above or below the type-wheels secured to said sleeves, substantially as and for the purposes set forth.

30. The combination, with a type-wheel shaft, two type-wheels secured to a loose sleeve 90
thereon, a local-battery circuit, two independent electro-magnets with their actuating devices for shifting the type-wheels, means, substantially as described, for holding the ink-roller and shifting it with the type-wheels, studs, 95
stud-pins secured to the top plate, upon which adjustable sleeves are supported, and springs attached to said sleeves, of circuit-interrupting devices secured to said shaft, a battery-circuit, a double-point relay, circuit-keys and 100
a sunflower, substantially as described, electro-magnets wound with parallel coils, a polarized armature controlled thereby, and a printing electro-magnet and its actuating devices, substantially as and for the purposes set 105
forth.

31. The combination of type-wheel electro-magnets and a unison electro-magnet in separate local circuits of the same battery, the type-wheel electro-magnets, but not the unison 110
electro-magnet, being responsive to short impulses to effect regular continuous rotation of the type-wheels, the unison electro-magnet being responsive only to prolonged pulsations for releasing the unison-arm, means, substantially such as described, for transmitting short and long impulses of the line-battery, a double-point relay in said line, and means, substantially such as described, for dividing the impulses in the local circuit during the prolongation of the impulses in the line-circuit and directing the circuits so that impulses of normal duration will energize the alternate coils of 115
said type-wheel magnets, while prolonged impulses of twice the duration energize the unison-magnet, substantially as and for the purposes set forth.

32. The combination, with a paper-carriage consisting of a curved plate having side bars attached thereto carrying feed-rollers, pressure-rollers, paper-roller, rack, and wheels, of rails secured to the rear of the instrument over which said wheels travel, means, substantially as described, for actuating said carriage, a 120
125
130

printing electro-magnet and a hammer actuated thereby supported upon a bracket secured to the instrument, a shaft with double type-wheels on a loose sleeve thereon, an ink-
5 roller supported upon a swinging arm, and means, as described, for shifting said ink-roller and type-wheels simultaneously, substantially as and for the purposes set forth.

33. The combination, in an automatic sign-
10 naling device, of a single-line circuit, a double-point relay in said circuit, escapement electro-magnets in local circuits controlled by said relay, a sunflower in the transmitter, a releasing-key, a paper-carriage, and means, sub-
15 stantially as described, for closing the line-circuit and releasing the paper-carriages of the transmitter and receiver, and a circuit-interrupting device attached to the receiver and actuated by the recoil movement of its paper-
20 carriage, interrupting the line circuit and permitting rotation of the type-wheels while said releasing-key is depressed, substantially as de-
scribed.

34. The combination, substantially as hereinbefore set forth, of a line-battery circuit, keys with open and closed circuit springs, and a short-circuiting key in the circuit of said battery, a sunflower, substantially as described, a type-wheel shaft and means for rotating the
3 same, a double-point relay in said circuit, a local-battery circuit, neutral-escapement electro-magnets included therein, a polarized armature controlled thereby, a scape-wheel on said shaft controlled by said polarized armature, insulated contact-points, a circuit-interrupting lever and spring attached to the instrument, a paper-carriage, means, substantially as described, for actuating said carriage, and a pawl attached thereto for actuating said
35 lever and operating to break the main-line circuit by the recoil movement of said paper-carriage.

35. The combination of a battery and two conductors connecting the poles thereof, a pulsator in the respective circuits, two neutral
45 **U** electro-magnets so arranged that their poles confront each other and with their two separate coils so connected to one another and in the respective circuits that the currents of the
50 same polarity traverse said coils alternately in reverse directions around the cores of said electro-magnets, and a permanently-polarized armature pivoted between said poles and vibrated in response to such pulsations, substan-
55 tially as and for the purposes set forth.

36. The combination, in a circuit-interrupting device, of a type-wheel shaft, hubs secured thereto, an insulating-sleeve supported thereby, a metallic sleeve secured to said insulated
60 sleeve, metallic disks and intermediate insulating disks secured thereto, and insulated contact springs bearing on said device, substantially as and for the purposes set forth.

37. The combination, with a transversely-
65 traveling paper-carriage, of a ratchet electro-magnet with its armature, lever, and retracting-spring, a pawl pivoted thereto, a stud and

a counter-pawl pivoted to the same, a link connecting said counter-pawl with said lever, a stud and a dog pivoted to said stud, and a
70 rack and counter-rack secured to the paper-carriage, substantially as and for the purposes set forth.

38. The combination, with a transversely-traveling paper-carriage, of a releasing electro-magnet with its armature, lever, and retracting-spring, a bar pivoted to said lever, pins therein, pawl, dog, counter-pawl, rack, and counter-rack, all arranged and operating substantially as described.
75

39. The combination, with a transversely-traveling paper-carriage, a ratchet electro-magnet with its armature, lever, and retracting-spring, a pawl pivoted thereto, a stud and a counter-pawl pivoted to the same, a stud
80 and a dog pivoted to said stud, and a rack and counter-rack secured to said carriage, of a releasing electro-magnet with its armature, lever, and retracting-spring, a bar pivoted to said lever, and pins attached thereto in rear of
85 said pawls and dogs, substantially as and for the purposes set forth.
90

40. The combination of a bracket secured to the rear of the instrument, a printing-magnet supported thereby, its armature, lever, 95 retracting-spring, and adjusting-screw, a sleeve secured to said bracket, a printing-hammer on a stem moving freely within said sleeve and in contact with said armature-lever, and a helical spring surrounding said stem, substantially
100 as and for the purposes set forth.

41. The combination, in a printing-telegraph instrument, of an independent frame supported on a base-plate, a hollow cylinder supported on said frame, a sunflower supported
105 in said cylinder, and a bed-plate with an aperture therein for admitting said cylinder, all arranged so that the bed-plate can be removed without disturbing said sunflower and the conductors leading therefrom to the contact-springs of the transmitting-keys, substantially
110 as described.

42. The combination, substantially as hereinbefore set forth, of a bed-plate carrying the electro-magnets and actuating devices, removable posts secured to said bed-plate, removable corner-posts, a top plate secured to said posts, and bevel glass sides secured between the bed and top plates and posts and so arranged that by the removal of the corner-
120 posts the glass may be removed without disturbing the operative devices, giving ready access for adjustment, substantially as described.
115

43. The combination of a battery, two branch lines from one electrode thereof, neutral-escapement electro-magnets in said circuit, electrical devices for closing the circuits alternately in reverse direction through the coils of said electro-magnets, a polarized armature controlled thereby, a type-wheel shaft controlled by said armature, a circuit-director on said shaft, and printing electro-magnets included in parallel circuit with the escapement
125
130

electro-magnets by means of said director, substantially as and for the purposes set forth.

44. The combination, with a battery, two branch lines from one electrode thereof, two electro-magnets wound with parallel coils in said circuit, electrical devices for closing the circuits alternately in reverse direction through the coils of said electro-magnets, a polarized armature controlled thereby, a type-wheel shaft controlled by said armature, a director on said shaft, and a ratchet electro-magnet included in parallel circuit with said electro-magnets by means of said director, of a paper-carriage and means operated by said ratchet electro-magnet for actuating the same, substantially as and for the purposes set forth.

45. The combination, with a battery, two branch lines from one electrode thereof, neutral-escapement electro-magnets in said circuit, electrical devices, substantially as described, for closing the circuits alternately in reverse direction through the coils of said electro-magnets, a polarized armature, a type-wheel shaft, and a circuit-director on said shaft, of a paper-carriage, its feed-rollers, and electro-magnet with its actuating devices, said feeding electro-magnet included in parallel circuits with said escapement electro-magnets by means of said director, substantially as and for the purposes set forth.

46. The combination, with a battery, two branch lines from one electrode thereof, neutral-escapement electro-magnets in said circuit, electrical devices for closing the circuit alternately in reverse direction through the coils of said electro-magnets, a polarized armature, a type-wheel shaft, and a circuit-director on said shaft, of a paper-carriage, a rack and counter-rack, and a releasing electro-magnet with its actuating devices, said electro-magnet being included in parallel circuit with said escapement electro-magnets by means of said

director, substantially as and for the purposes set forth.

47. The combination, with a battery, two branch lines from one electrode thereof, neutral-escapement electro-magnets in said circuit, electrical devices for closing the circuit alternately in reverse direction through the coils of said electro-magnets, a polarized armature, a type-wheel shaft and two type-wheels on a loose sleeve thereon, and a circuit-directing device secured to the type-wheel shaft, of two independent electro-magnets with their actuating devices for shifting the type-wheels, said electro-magnets being included in parallel circuit with said neutral-escapement electro-magnets by means of said circuit-directing device, substantially as and for the purposes set forth.

48. The combination of a battery, two branch lines from one electrode thereof, neutral escapement electro-magnets in said circuit, electrical devices for closing the circuit alternately in reverse direction through the coils of said neutral-escapement electro-magnets, a polarized armature, a type-wheel shaft, a circuit-correcting device and unison-arm thereon, and a unison electro-magnet with its actuating devices, said unison electro-magnet being included in parallel circuit with the neutral-escapement electro-magnets by means of said correcting device and responding to pulsations of twice the duration of those employed to actuate the neutral-escapement electro-magnets, substantially as and for the purposes set forth.

In witness whereof I have hereunto set my hand in presence of two subscribing witnesses.

JACOB H. LINVILLE.

Witnesses:

HERMANN BORMANN,
THOMAS M. SMITH.
